UNITED STATES PATENT OFFICE.

ALFRED M. LA CHAPELLE, OF SPRINGFIELD, MASSACHUSETTS, AND SAMUEL BENENSOHN, OF CHICAGO, ILLINOIS.

CARBURETER.

1,290,246.

Specification of Letters Patent. Patented Jan. 7, 1919.

Application filed March 8, 1916. Serial No. 82,800.

To all whom it may concern:

Be it known that we, ALFRED M. LA CHAPELLE and SAMUEL BENENSOHN, citizens of the United States, and residents, respectively, of Springfield, Hampden county, Massachusetts, and of Chicago, in the county of Cook and State of Illinois, have invented certain new and useful Improvements in Carbureters; and we do hereby declare that the following is a full, clear, and exact description thereof, reference being had to the accompanying drawings, and to the letters of reference marked thereon, which form a part of this specification.

15 This invention relates to improvements in carbureters and consists of the matters hereinafter described and more particularly pointed out in the appended claims.

The object of the invention is to provide 20 a carbureter which is simple and economical in construction and which is greatly superior in efficiency to the carbureters heretofore in use.

Our improved carbureter is of such construction and operation that a free body of 25 fuel is maintained in the carbureter, with substantially its entire surface exposed to the suction of the engine, said body being replenished from a suitable source of supply 30 by being automatically drawn into the fuel chamber of the carbureter by the suction of the engine, it being immaterial whether said source is located in a plane above or below that of the carbureter. Our improved carbureter also includes an efficient spraying 35 device whereby the fuel is broken up into finely divided particles just before it is mixed with the incoming air so that it is impossible to deliver to the engine a mixture 40 too rich for the efficient operation of the engine. The carbureter is also so constructed that the finely divided particles of fuel 45 condensed on its walls are delivered back to the body of fuel in the carbureter, thus obviating a flooding of the spraying device 50 and the delivery to the engine of fuel in liquid form.

All of the before mentioned objects and 55 advantages will be apparent as we proceed with our specification.

In the drawings:

Figure 1 is a view in side elevation of a carbureter made in accordance with our invention.

55 Fig. 2 is a top plan view thereof.

Fig. 3 is a vertical central sectional view through our improved carbureter, the plane of the section being indicated by the line 3—3 of Fig. 2.

Fig. 4 is a horizontal sectional view there- 60 through taken in a plane indicated by the line 4—4 of Fig. 3.

Fig. 5 is a detail vertical sectional view through the atomizing or spraying device and will be more specifically referred to 65 later.

Referring in detail to that embodiment 70 of our invention as illustrated in the accompanying drawings:—10 indicates the carbureter bowl which is open at the top. Said 75 bowl has a bottom wall 10^a from which depends an interiorly threaded flange 11. Concentrically arranged within said bowl and extending upwardly from the bottom wall thereof is an annular flange 12, which 80 terminates at its top a short distance below the top of the bowl and which defines a passageway of comparatively large cross-sectional area as compared to the cross-section of the bowl.

The space between said flange 12 and the upright wall of the carbureter bowl 10 provides an annular reservoir or chamber which is adapted to contain a body of the fuel to 85 be carbureted.

16 indicates a laterally extending hollow boss made integral with the bowl 10. Said boss provides a fuel inlet chamber which communicates with the annular reservoir in the said bowl. In the bottom wall of said 90 hollow boss is provided an inlet aperture 18; 17 indicates a pipe fitting adapted to be connected to a pipe leading from the fuel supply tank (not shown) and secured by a suitable coupling 17^a to the boss 16 in line 95 with the inlet aperture 18.

23 indicates a float which controls the level of the fuel in the annular fuel chamber of the carbureter body in a familiar manner. Said float is preferably made of cork and is 100 of the familiar horse-shoe shape, surrounding but spaced from the annular flange 12 in the carbureter bowl. Said float is fixed to one arm of a lever 20, pivoted on a pin 20^a in the side walls of the boss 16. From the 105 other arm of said lever depends a valve stem 24 having a conical valve plug 25 at its bottom end which is adapted to close upon a valve seat formed about the inner end of the inlet aperture 18.

80

110

The valve stem 24 is connected to the lever 20 by means of a ball and socket joint 27. The laterally extending hollow boss 16 is provided in its top wall with the usual inspection opening closed by a screw threaded plug 28.

30 indicates a fitting which forms the top of the carbureter. Said fitting consists of a tubular neck portion 38, the bottom end of which terminates in a downwardly and outwardly flared flange 38^a which closes at its peripheral edge upon the open top of the carbureter bowl 10. This flange 38^a has radially extending ears 32 which are attached by screws 31 to similarly disposed ears 33 on the carbureter bowl 10. To make a gas tight joint a gasket 35 is interposed between the top of the carbureter bowl and the bottom of the flange 38^a. The top of the fitting 30 has laterally extending ears 41 by means of which it is attached to the elbow fitting of the engine inlet manifold (not shown).

In the neck 38 of the fitting 30 is provided the usual throttle valve disk 43 fixed to a transverse shaft 44 having bearing in the tubular wall of said neck.

45 indicates the operating lever of the throttle valve attached to the shaft 44. 48 indicates the usual adjustable stop screw for limiting the movement of said operating lever.

55 indicates an upright tube coaxially arranged as shown within the annular flange 12 of the carbureter bowl. Said tube is supported by a spider 51, the arms 50 of which are fixed to the top end of the annular flange 12. The bottom end of said tube 55 depends through the bottom wall 93 of a cup-like valve casing 91 which has threaded engagement with the flange 11 at the bottom of the carbureter bowl 10. The bottom end of the tube 55 is threaded to receive a nut 99 which is engaged against the said bottom wall 93. The top end of the tube 55 extends above the top of the flange 12 and is flared outwardly for a purpose which will presently appear.

58 indicates a horizontal spraying or atomizing tube which extends through diametrically opposite apertures provided therefore in the primary air tube 55, just above the top end of the flange 12. Said tube 58 has a closed end 58^a. The other end of said tube is bent downwardly to provide a substantially vertical part 60 which extends into the annular fuel chamber formed as before mentioned, and terminates a short distance above the bottom wall 10^a of the carbureter bowl where it is cut at an angle to provide an enlarged inlet opening. Said vertical part 60 is engaged by an ear 61 on the flange 12.

In the atomizing or spraying tube 58 are provided a pair of vertically aligned aper-

tures 70, 72, which are coaxial with respect to the axis of the tube 55. The bottom aperture 70 is of smaller diameter than the upper aperture 72 for a reason which will shortly appear. Below the tube 58 the inner diameter of the tube 55 is restricted as shown at 55^a but is greater than the diameter of the tube 58 so that a part of the air that passes up through tube 55 will pass up around the spraying tube 58.

The valve casing 91, depending from the carbureter bowl 10, has a plurality of annularly spaced ports 96, 96, which are normally closed by a piston valve member 94 located in and adapted for vertical movement in said valve casing. Said valve member is hollow and has a bottom wall 94^a which closes openings 92 in the bottom wall 93 of the valve casing 91, which openings expose the bottom wall of the piston valve member to atmospheric pressure. The said valve member has annularly arranged ports 97 which are adapted to register with the ports 96 in the valve casing when the valve piston is raised. A coiled spring 95, interposed between the spider 51 near the top of the tube 55 and the bottom wall 94^a of the valve member 94 normally holds said valve member in its lowest position against the bottom wall 93 of the valve casing so that the ports 97 are closed.

The operation of the improved carbureter is as follows, and we shall start with the carbureter empty and containing air at atmospheric pressure. The gasoline tank to which the carbureter is operatively connected, we will say, is located in a plane below that of the carbureter, and atmospheric pressure maintains in the interior of said tank. Under these conditions the float 23 is in its lowest position in the fuel chamber and the inlet valve plug 25 is raised from its seat. The inlet passage 18 connected to the supply line is open and the piston valve member 94 is held in its closed position by the spring 95.

The throttle valve 43 is now opened to provide a free passage through the fitting 30 to the inlet manifold of the engine cylinders. The crank shaft of the engine is then "turned over" as by means of a hand crank or electric starter as usual. The suction stroke of the pistons will displace a volume of air from the interior of the carbureter and although the tube 55 admits air into the carbureter to take the place of the displaced air, the air in the carbureter is displaced more rapidly than it can be admitted or drawn through the restricted passage 55^a in said tube. This displacing of the air in the carbureter will produce a partial vacuum in the whole interior of the carbureter body, which will be intensified as the crank shaft gains speed in its preliminary "turn over."

As the air is withdrawn from the interior

of the carburetor more rapidly than it can be replaced by the inrush of air through the tube 55, which we may call the primary air inlet, a partial vacuum will be produced in the carburetor which will be exerted on the next point of least resistance, that is the supply line leading to the fuel inlet 18. This will act to draw or suck into the fuel chamber within the bowl 10 of the carburetor a quantity of fuel (it being borne in mind that the fuel tank is at atmospheric pressure). This drawing of fuel into the bowl of the carburetor will continue until the rising fuel level causes the float 23 to seat the valve plug 25 and close off the flow of fuel through the inlet 18. The rising level of the fuel in the fuel chamber will submerge the bottom end of the upright part 60 of the atomizing or spraying tube 58. With the bottom end of the atomizing tube submerged or sealed, a part of the air passing up through the primary air inlet tube 55 will pass through the atomizing openings 70, 72, in the tube 58. That part of the primary air which does not pass through said opening will pass about the sides of the atomizing tube into the outwardly flared top end of said primary air tube (see Fig. 5) to mix with the atomized particles of fuel as will appear later.

This construction provides a Venturi tube effect and such air as passes through the openings 70, 72, in the atomizing tube 58 will create a greater vacuum in said tube than is maintained in the annular fuel chamber with the result that a column of fuel is drawn up into the tube 58. As soon as the fuel reaches the atomizing openings 70, 72 it is carried out through the aperture 72 in the form of a finely divided spray of mixed fuel and air which will intermingle and mix with additional air in the outwardly flared top end of the tube 55 which has passed up about the sides of said atomizing tube. The air is thoroughly mixed with the atomized fuel in said flared mouth and the mixture will then pass through the neck 38 beyond the throttle valve 43 to the inlet manifold of the engine, where it will be distributed to the various cylinders. The proper mixture now being delivered to said engine cylinders and the ignition system being in order, the engine now "turns over" under its own power, and the preliminary driving influence (the hand crank or other starter) may be discontinued.

As the engine crank shaft gains in speed, the vacuum in the interior of the carburetor bowl will be increased. As the piston valve 91 is subjected to atmospheric pressure on its bottom side and to the pressure in the interior of the carburetor plus the pressure of the spring 95 on its top side, said valve will tend to rise against the restraining action of the spring 95 until the ports 97 begin to uncover the ports 96 in the valve casing

91. The secondary air supply admitted through said ports will rush up into the carburetor, striking the flared flange of the fitting 30 whence it will be directed into a position above the tube 55 to mix with and reduce the "richness" of the mixture issuing from the said tube under the increased suction due to the increased speed of the engine. The rush of air up through the neck 38, which is somewhat smaller in diameter than the flange 12, will produce a forced draft upon the air above the body of fuel in the fuel chamber and in the hollow extension 16 which will act to further increase the vacuous condition in the fuel chamber and in said extension.

As the fuel is used, the level of the body of fuel in the fuel chamber will drop. The float 23 falls with the fuel level and opens the valve 25 of the fuel inlet 18. More fuel is sucked in through said inlet opening (it being remembered that only atmospheric pressure exists in the fuel supply tank) until the float again rises and closes off said inlet 18. Should the engine begin to "race", the throttle 43 may be partially closed, restricting the passage in the neck 38. The supply of mixture to the engine being thus diminished, the engine will begin to slow down, decreasing the suction in the carburetor. The spring 95 will then return the valve 94 to a closed position so as to shut off the secondary air supply. Such air as is now being drawn into the carburetor enters only through the primary air inlet tube 55, the amount being further diminished as the throttle is more and more closed, until just enough air enters to properly atomize the fuel and cause the supply to be renewed in the fuel chamber. The ignition system may now be cut out and the engine stops, with a proper level of fuel in the annular fuel chamber and atomizing tube, the float closing over the inlet 18, atmospheric pressure now existing in said carburetor. The engine of course may again be started in a great deal less time as the annular fuel chamber now has the necessary fuel therein.

Such fine particles of fuel as condense on the walls of the fitting 30 will drop into the fuel body in the fuel chamber to be used over again.

When the fuel supply tank is located above the carburetor, the results will be the same as far as the "force feed" of the fuel is concerned during the operation of the engine, the only difference being that said fuel will be initially admitted to the fuel chamber by gravity until shut off by the valve 25 of the float 23.

It is apparent that a direct draft or suction is afforded between the engine cylinders and the body of fuel in the fuel chamber of the carburetor, which results in the "forced feed" or drawing of fuel from the fuel sup-

ply tank. The primary air is admitted through a straight upright tube which does away with the dead pockets or spaces which act to restrict the free passage of air therethrough, this being one of the objections to nearly all of the present type of carbureters.

Our improved carbureter is simple in construction and comprises but few moving parts, thus reducing the tendency to get out of order and makes it easy to inspect or clean as the case may be.

It automatically adjusts itself to feed just the amount of air and fuel needed in the proper mixture for the operation of the engine at its desired speed, the feed being determined by the suction or pull of the engine upon the surface of the body of fuel in the fuel chamber. Another advantage gained is owing to the atomizing or spraying device being located in a plane a distance above the level of the fuel in the fuel chamber, the atomizing opening cannot be "flooded" so as to deliver liquid fuel to the engine as actually now happens when the car is ascending a grade or is rocked or jarred about as when the car is traveling over rough roads.

While in describing our invention we have referred to certain details of mechanical construction and arrangement of parts, we do not wish to limit ourselves thereto except as may be pointed out in the appended claims.

We claim as our invention:

1. A carbureter comprising a fuel bowl defining an annular, open top fuel chamber, a cap on said bowl adapted to be connected to an engine whereby the suction of the engine is exerted upon the fuel in said chamber, a float in said chamber for controlling the inlet of fuel thereto, a primary air inlet tube open at one end to the atmosphere, and a spraying tube having an upright inlet end connected with said fuel chamber and having a horizontal discharge end extending across said primary air inlet tube, said discharge end having vertically alined spraying apertures in said primary air tubes.

2. A carbureter comprising a fuel bowl defining an annular, open top fuel chamber, a cap on said bowl adapted to be connected to an engine, whereby the suction of the engine is exerted upon the fuel in said chamber, a float in said chamber for controlling the inlet of fuel thereto, a primary air inlet tube open at one end to the atmosphere and having its other end extending into said cap, and a spraying tube having an upright inlet end connected with said fuel chamber and having a horizontal discharge end extending across said primary inlet tube at a point below its top end, said discharge end of the spraying tube having vertically alined spraying apertures in said primary air tube, that part of said primary air inlet tube above

said horizontal, apertured part of said spraying tube providing a primary mixing chamber.

3. A carbureter comprising a fuel bowl defining an annular, open top fuel chamber, a cap on said bowl adapted to be connected to an engine whereby the suction of the engine is exerted upon the fuel in said chamber, a float in said chamber for controlling the inlet of fuel thereto, a primary air inlet tube open at one end to the atmosphere, and a spraying tube having an upright inlet end connected with said fuel chamber and having a horizontal discharge end extending across said primary air tube, said discharge end having vertically alined spraying apertures in said primary air tube, said primary air tube being restricted in diameter below said discharge end of the spraying tube.

4. A carbureter comprising a fuel bowl defining an annular, open top fuel chamber, a cap on said bowl adapted to be connected to an engine whereby the suction of the engine is exerted upon the fuel in said chamber, a float in said chamber for controlling the inlet of fuel thereto, a secondary air valve closing the bottom end of said fuel bowl, a primary air inlet tube extending through said secondary air valve and open to the atmosphere, and a spraying tube having an upright inlet end connected with said fuel chamber and having a horizontal discharge end extending across said primary air inlet tube, said discharge end having vertically alined spraying apertures in said primary air tube.

5. A carbureter comprising a fuel bowl, including an upright, tubular flange, said flange defining a secondary air inlet and a surrounding annular fuel chamber, a float in said chamber for controlling the admission of fuel thereto, an automatic valve normally closing said secondary air inlet, a primary air inlet tube in and surrounded by said secondary air inlet, said primary air inlet tube extending through said automatic valve and opening to the atmosphere, and a spraying tube having an upright inlet end connected with said fuel chamber and having a horizontal discharge end extending across said primary air tube, said discharge end having vertically alined, spraying apertures in said primary air tube.

6. A carbureter comprising a fuel bowl, including an upright, tubular flange, said flange defining a secondary air inlet and a surrounding annular fuel chamber, a float in said chamber for controlling the admission of fuel thereto, an automatic valve normally closing said secondary air inlet, a primary air inlet tube in and surrounded by said secondary air inlet, said primary air inlet tube extending through said automatic valve and opening to the atmosphere, and a spraying tube having an upright inlet

end connected with said fuel chamber and having a horizontal discharge end extending across said primary air tube, said discharge end having vertically alined, spraying apertures in said primary air tube, and said primary air tube and said spraying tube being adjustable vertically of and supported on said upright, tubular flange.

7. A carbureter comprising a fuel bowl, including an upright, tubular flange, said flange defining a secondary air inlet and a surrounding annular fuel chamber, a float in said chamber for controlling the admission of fuel thereto, an automatic valve normally closing said secondary air inlet, a primary air inlet tube in and surrounded by said secondary air inlet, said primary air inlet extending through said automatic valve and opening to the atmosphere, and a spraying tube having an upright inlet end connected with said fuel chamber and having a horizontal discharge end extending across said primary air tube, said discharge end having vertically alined spraying apertures in said primary air tube, and said primary air inlet tube being restricted in diameter below said spraying tube and being enlarged above the same to provide a mixing chamber.

8. A carbureter for combustion engines comprising a fuel bowl having a fuel inlet port, said bowl being adapted to contain a free body of fuel having a comparatively large surface area, a spraying device located in said bowl adapted to be supplied from the fuel contents of said bowl, an air inlet and mixing tube associated with said spraying device and through which said spraying device extends, said spraying device including a transverse tube part which has alined apertures of different diameters coaxial with said air inlet tube, a valve adapted to close said fuel inlet port, a float in said bowl operatively connected with said valve, and a cap for said bowl, said cap providing a discharge passage of a cross sectional area somewhat smaller than the surface area of the fuel in said bowl, a secondary mixing chamber, and means providing a secondary air inlet adapted to admit air to said secondary mixing chamber when the pressure therein is reduced to a predetermined point.

9. A carbureter for combustion engines comprising a fuel bowl provided with a fuel

inlet port, said bowl having an upright side wall, a bottom wall and an upright annular flange spaced within said side wall, said flange and side and bottom walls defining an annular fuel chamber, a spraying device located in said bowl and adapted to be supplied from the body of fuel in said annular chamber, a tube providing a primary air inlet and a mixing chamber associated with said spraying device, a spring controlled secondary air inlet valve mounted on said tube, a float-controlled-valve for closing said fuel inlet port when the fuel is at a predetermined level in said chamber, and means providing a cover for said bowl and conduit adapted to connect said bowl with the engine, whereby the suction action of the engine is exerted over the entire surface of the body of fuel in said chamber.

10. A carbureter for combustion engines comprising a bowl having a fuel inlet port, said bowl being adapted to contain a body of fuel presenting a comparatively large surface area, an air inlet tube extending into said bowl and a mixing tube connected therewith, a spraying device comprising a bent pipe, one leg of which is open and extends into said fuel chamber and the other of which is closed, said last mentioned leg extending transversely through said air inlet tube and being provided with Venturi openings in axial alinement with said air inlet tube, said inlet tube being of reduced internal diameter adjacent said Venturi tube openings but being larger in diameter than the tube forming said spraying device, a valve adapted to close said fuel inlet port, a float in said bowl operatively connected with said valve, and a cap for said bowl adapted for connection to the engine, said cap providing a conduit of somewhat smaller cross sectional area than the surface area of the fuel in said bowl.

In testimony that we claim the foregoing as our invention we affix our signatures in the presence of two witnesses, this 17th day of February A. D. 1918.
